UNITED STATES PATENT OFFICE.

HARRIS D. HINELINE, OF PITTSBURGH, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed February 3, 1923. Serial No. 616,767.

My invention relates to thermal relays of the cartridge type and more particularly to means for indicating the energization thereof.

5 One object of my invention is to provide means for indicating the degree of energization of a thermal relay of the cartridge type.

Another object of my invention is to provide means for indicating the degree of energization of a relay of this character which is responsive to the temperature of the entire relay.

10 It is also an object of my invention to provide a thermal relay which is simple to manufacture and of rugged construction.

15 It is a further object of my invention to provide a primary thermal-responsive member for controlling a relay circuit upon conditions of overload in a primary circuit, and, also, to provide a secondary thermal-responsive element for indicating the degree of energization, or the thermal state, within the relay.

20 In cartridge relays, as heretofore constructed, no means have been provided for indicating the degree of energization of the relay member until a reaction took place which was indicated by the interruption of the electrical circuit protected by the relay member. By my invention, I provide means for indicating the degree of energization, or the thermal condition, of the relay at all times, so that warning may be had of the condition of the relay in advance of the 25 actual tripping of the main electrical circuit, thereby permitting employment of means for relieving conditions in that circuit other than the actual interruption thereof.

30 Figure 1 of the drawing is a longitudinal sectional view of a thermal relay embodying my invention.

35 Fig. 2 is a longitudinal sectional view of the relay taken at right angles to that of Fig. 1.

40 Fig. 3 is a longitudinal sectional view, on an enlarged scale, of some of the parts shown in Fig. 2.

45 Fig. 4 is a view, in transverse section, of my thermal relay, showing the position of the indicating means.

Fig. 5 is an edge view, partly in section, of a metallic cylindrical element employed in my invention.

50 Fig. 6 is an end view of the same.

Figs. 7, 8 and 9 are views of parts of the indicating mechanism embodied in a preferred form of my invention.

55 Fig. 10 is a detail view of the assembled parts of my preferred form of indicator.

Fig. 11 is a sectional detail view, similar to Fig. 3, of another form of my invention.

60 Fig. 12 is a detail view of the modified form of indicator.

65 Similar reference numerals in the several views indicate like parts.

In the preferred form of my invention, I utilize a tube or cylinder 1 of insulating material which is preferably in the form of a plurality of layers of prepared paper or micarta. I close the ends of the cylinder 1 by suitable insulating bushings 3 held in place by metallic ferrules 4 and screws 5, with terminal conductors 6 projecting through the bushings.

70 An inner cylindrical member 7, which is shown in detail in Figs. 5 and 6, is secured within the cylinder 1 in any suitable manner, as by screws 8 and 9. One end of the member 7 is preferably cut off at an oblique angle to the axis of the cylinder to provide 75 a tapered end 12. The other end of the cylinder 7 is provided with diametrically opposed slots which extend longitudinally thereof.

75 A bimetallic element 10 is so mounted within the member 7 that the edges of an end portion thereof are disposed in the opposed, longitudinally extending slots located in the member 7. The edges of the element 10 may be maintained in positive 90 electrically conductive relation with the member 7 by soldering or brazing them thereto. The element 10 is also provided with a tapered end or tongue portion 14 which is free to move within the member 7. 95

80 A pair of tail pieces 13 are clamped on both sides of the lower portion of the element 10, both of which are provided with end portions that are bent at an angle thereto and which project beyond the soldered 100

portion of the element 10. One end of a flexible conductor 15 may be secured to the flexible portions of the members 13. The flexible conductor 15 connects the tail piece 13 to the adjacent terminal conductor 6. Within the inner end of the member 7 and surrounding the end of the tongue 14, is a band of insulating material 16 and a band of conducting material 17. An adjustable screw 10 or plug 18, supported by the band 17, extends through openings in members 1 and 7, to constitute means for adjusting the normal position of a contact member 19 with which the end of the tongue 14 is provided. 15 A friction member 18^a is provided to hold the screw 18 in any desired position. A screw 21 is also mounted in registering openings in the members 1 and 7 to constitute an electrical connection between the band 17 20 and an external conductor 22.

An indicating mechanism 23 is mounted on the end 12 of the member 7. A flexible conductor 24 connects the tip of end 12 of the member 7 to the adjacent terminal conductor 6. The resistance of the flexible conductors 15 and 24 is such that the amount of heat generated thereby is sufficient to provide the heat loss at the ends of the device by reason of the heat conducted away thereby from the terminal conductors 6.

Indicator 23, as shown in Figs. 4 and 10, comprises a frame 25 of U-shape which is secured, by devices 26, to the end 12 of cylinder 7. A thermally-responsive bimetallic spiral spring 27, is secured, as at 28, to portion 12 of cylinder 7 and to a spindle 29 that is adjustably mounted on the arms 31 of member 25. An arm 32 is rigidly secured to the spindle 29.

40 In the form of my invention shown in Figs. 1 to 10, inclusive, arm 32 is provided with a plate 33 calibrated to indicate units of current, temperature or percentage of energization, as desired. The development of 45 this indicator is shown in Figs. 7, 8 and 9, Fig. 7 being a plan view thereof, Fig. 8 an end view thereof, and Fig. 9 a detail of the blank from which members 32 and 33 are shaped. An opening 34 is provided in the 50 cylinder 1 at a point opposite the indicator 33 for co-operation therewith (see Fig. 3). This opening may be provided with a window member such as mica, if desired.

In the form of my invention shown in 55 Figs. 11 and 12, an arm 35 is attached to the spindle 29 and extends through an opening 36 in the cylinder 1, and co-operates with a scale 37 affixed to the exterior of the cylinder 1. A plate 38 is attached to the 60 arm 35 to prevent the entrance of foreign bodies into the cylinder 1 through the opening 36.

In the operation of my invention, a electrical circuit is connected to the conductor 65 6 by suitable means (not shown). The cur-

rent then traverses the conductors 6 and 15 to the tail piece 13. By referring to Figs. 1, 2 and 5, it may be observed that the members 10 and 25 are insulated by air from the ends of the device. The current on leaving 70 the tail piece 13 traverses the bimetallic element 10 and then the metallic cylinder 7 and generates heat in accordance with the well known I^2R rule. This current is again collected at the tip 12 of the cylinder 7, from 75 whence it traverses conductors 24 and 6 to the external circuit. The combined heat generated by the current traversing the members 13, 10 and 7 affects the free end 14 of the bimetallic element 10, and when 80 the latter reaches a predetermined maximum temperature the element 14 is distorted until the movable contact member 19 is disengaged from the fixed contact member 18, which causes an external circuit to be 85 opened in a manner and with results, well known in this art.

The heat generated by the current in the various metallic portions of the relay are 90 transferred to the spring 27 which is thermally responsive. As the temperature increases, the distortion of the spring 27 increases in proportion, with an accompanying turning of the spindle 29, arm 32 and indicator 33. It is apparent that the indicia 95 of the indicator 33, which is opposite the opening 34 in the cylinder 1, is a guide to the temperature condition within the relay member, and the temperature condition is, in turn, an indication of the integrated 100 amount of electrical energy traversing the relay member, which is preferably in series connection with the circuit to be protected.

An attendant, upon observing the readings 105 on scale 37 or window 34 is able to tell when a dangerous condition exists in the relay, and he may then take other steps to relieve the condition of the circuit without interruption thereof.

In the modification shown in Figs. 11 and 110 12, the rotation of spindle 29 causes an arm to move externally of the spindle in relation to the scale 37, the operation of the two forms of relays being otherwise the same.

It may thus be seen that I have provided 115 a thermal relay which indicates externally its degree of energization at all times, directly in proportion to the temperature affecting the bimetallic thermal relay member. The construction of my cylinders provide a 120 uniform zone of temperature between the bimetallic relay element and the indicator which temperature is substantially in accordance with the value of the current traversing the device. While I have shown my invention in its preferred form, it is apparent 125 that modifications may be made in the arrangement of circuits and apparatus employed without departing from the spirit of my invention. I desire, therefore, to be 130

limited only by the scope of the appended claims.

I claim as my invention:

1. In a thermal relay of the cartridge type, the combination with a heat-producing bimetallic thermo-responsive member, of means actuated by the heat produced by the thermo-responsive member for indicating the degree of energization of said relay.
2. In a thermal relay of the cartridge type, the combination with a current-conducting bimetallic thermo-responsive member, of thermo-responsive means, electrically independent of said current-conducting thermo-responsive member for indicating the degree of energization of said relay.
3. In a thermal relay of the cartridge type, the combination with a current-conducting bimetallic thermo-responsive member, of thermo-responsive spring means, electrically independent of said current-conducting thermo-responsive member for indicating the degree of energization of said relay.
4. In a thermal relay of the cartridge type, the combination with a thermally responsive member, a metallic casing partially surrounding said thermally responsive member, and an outer casing surrounding said metallic casing, of thermally responsive means for indicating the degree of energization of said relay located within said outer casing.
5. In a thermal relay of the cartridge type, the combination with a thermally responsive member, a metallic casing partially surrounding said thermally responsive member, and an outer casing, having an opening therein, surrounding said metallic casing, of thermally responsive means, observable through said opening, for indicating the degree of energization of said relay and located within said outer casing.
6. In a thermal relay of the cartridge type, the combination, with a thermally responsive member, a metallic casing partially surrounding said thermally responsive member, and an outer casing surrounding said metallic casing, of thermally responsive means for indicating the degree of energization of said relay located within said outer casing and actuated in accordance with the temperature of the first-named thermally responsive member.
7. In a thermal relay of the cartridge type, an outer casing, an inner metallic casing partially filling said outer casing, a thermo-responsive member partially inclosed by said metallic casing and in electrical contact therewith, an electrical conductor extending through said outer casing and attached to said thermo-responsive member, an electrical conductor connected to said metallic casing and extending outside said outer casing, and an indicating means mounted on a portion 65 of said metallic casing and co-operating with an opening in said outer casing.
8. A thermo-responsive indicator comprising a current-conducting cylindrical frame, a shaft mounted axially of said cylindrical 70 frame, a thermally-responsive spring spirally mounted on said shaft, one end of said spring being secured to said frame, the other end of said spring being secured to said shaft, and an indicator controlled by said 75 shaft, whereby changes in the temperature of said device effect the actuation of said indicator.
9. In an electrical device, a casing, a current traversed thermally-responsive heat- 80 generating member disposed in said casing for disengaging a contact member at a predetermined temperature, and a thermally responsive member disposed in said casing for indicating the temperature thereof. 85
10. In a thermal relay, a thermo-responsive current-conducting member for disengaging a contact member at a predetermined temperature, a temperature indicator, and a casing for enclosing said thermo-responsive 90 member and said indicator and for maintaining a uniform temperature therewith.
11. In a thermal relay, in combination, a unitary heat-producing and heat-responsive means for disengaging a contact member, and a temperature-indicating means 95 associated therewith.
12. In a thermal relay, in combination, a heat-producing and heat-responsive means for disengaging a contact member and a 100 temperature-indicating means associated therewith, said heat-producing and heat-responsive means and said temperature-indicating means constituting a unitary structure. 105
13. In a thermal relay, the combination with an electrically-energized heat-producing and heat-responsive means, a temperature-indicating means, and an elongated casing for containing said two means, of current-traversed means in said casing, at each end thereof, for compensating for the flow of heat from said two means to the ends of said casing. 110
14. In a thermal relay, the combination with an electrically-energized heat-producing means, a circuit-controlling means thermally-actuated thereby, of a temperature-indicating means associated with said two means, and current-conducting heating 120 means for ensuring that the temperature of the heat-producing means and the temperature of the temperature-indicating means shall be substantially alike. 115
15. In a thermal relay of cartridge type 125 the combination with a current-conducting and heat-producing thermo-responsive circuit-controlling means, of current-conduct-

ing means for compensating for the flow of heat from said means to the ends of said relay.

16. In a thermal relay, the combination with an insulating casing, of a cylindrical current-conducting member located in said casing, a current-conducting thermo-responsive member located in and supported by said cylindrical member and effective to control an electrical circuit, a temperature indicator secured to said cylindrical member, terminal members at the ends of said casing,

and current-conducting means connected respectively to said thermo-responsive member and to said cylindrical member and to the 15 respective adjacent terminal members and effective to compensate for the flow of heat from said cylindrical member and said thermo-responsive member to the respective terminal members. 20

In testimony whereof, I have hereunto subscribed my name this 26th day of January, 1923.

HARRIS D. HINELINE.
